UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-DETECTING MECHANISM.

Application filed February 9, 1923. Serial No. 618,187.

To all whom it may concern:

Be it known that I, EPPA H. RYON, a citizen of the United States, residing at Waltham, in the county of Middlesex and State of Massachusetts, have invented a new and useful Weft-Defecting Mechanism, of which the following is a specification.

This invention relates to a mechanism for detecting substantial exhaustion of weft on the weft carrier of the running shuttle of an automatic weft replenishing loom. In looms using very fine weft or filling, such as fine cotton or silk looms, each weft carrier remains in the running shuttle for a relatively long period of time and the weft thereon makes a very great number of contacts with the weft detector. Such repeated contacts frequently result in wear and breakage of the filling by the weft detector and it is the general object of my invention to avoid or largely reduce this wear and breakage.

With this general object in view, my invention consists essentially in the provision of a contact member designed to engage the weft on a full weft carrier and to prevent contact of the weft with the weft detector until the supply of weft on the weft carrier is depleted to a predetermined extent and substantial exhaustion of weft is approaching.

For the attainment of this desired result, I have devised an exceedingly simple construction which involves the addition of few and simple parts to the weft detecting mechanism at present in use. Under normal running conditions, a supplementary contact member is locked from relative movement in the detector slide and receives the full thrust of the weft carrier, said member being provided with a broad smooth contact surface for such purposes. When the supply of weft is sufficiently reduced, however, the supplementary contact member is withdrawn from operative position and the subsequent exhaustion of the weft is indicated by the usual weft detector as in the previous practice.

My invention further relates to arrangements and combinations of parts which will be hereinafter described and more particularly pointed out in the appended claims.

A preferred form of the invention is shown in the drawings in which

Fig. 1 is a plan view of my improved weft detecting mechanism;

Fig. 2 is a side elevation thereof;

Fig. 3 is a partial sectional plan view taken along the line 3—3 in Fig. 2;

Fig. 4 is a detail sectional elevation, taken along the line 4—4 in Fig. 3, and

Figs. 5, 6 and 7 are sectional plan views with certain parts omitted and showing successive positions of the contact members.

Referring to the drawings, I have shown a weft detecting mechanism which is in general of the type disclosed in my prior Patent No. 1,352,536, issued September 14, 1920, and comprises a detector slide 10 mounted in a frame or casing 11 pivotally connected by a bolt 13 to a stand 14 projecting from the loom side (not shown). A bracket or angle 15 on the upper face of the slide 10 is provided with an opening to receive a rod 16 which supports a compression spring 17. The rod 16 is threaded at one end in the cover 18 of the casing 11 and may be adjusted therein to limit rearward movement of the slide 10 toward the running shuttle and the weft carrier therein. An adjusting screw 19 provides for vertical adjustment of the detector slide about its pivot 13. A fixed detector 20 is secured to the rear portion of the slide 10 in any convenient manner as by a clamping screw 21. A movable detector 22 is pivoted to the slide 10 by a screw or stud 23 and is positioned closely adjacent the fixed detector 20. A rod or link 24 (Figs. 3 and 5) is pivoted at 25 to a laterally projecting arm 26 of the movable detector 22 and extends forwardly through the slide 10.

The front end of the link 24 is pivoted at 27 to an arm 28 clamped to one end of a short horizontal shaft 29 rotatably mounted in bearings 30 and 31 projecting forward from the stand 14. A second arm 32 at the opposite end of the shaft 29 has a slotted connection to a plunger 33 slidable in a transverse opening in an upward projection 34 of the stand 14. The projection 34 is provided with a slot 35 in which a floating lever 36 is moved vertically by an actu-

ating plunger 37. At its opposite end the floating lever 36 is connected by a pivot 38 to a link 39 which extends upward to the indicating mechanism of the magazine 5 (no shown).

The parts thus far described are substantially of the usual construction as shown in my prior patent above noted and in themselves form no part of my present invention.

10 Reference may be had to that patent and to U. S. Patent No. 972,772, issued to me October 11, 1910, for a more complete description and for details of the construction and operation of the indicating mechanism.

15 My present invention relates particularly to the provision of a supplementary contact member 40 which is mounted to slide longitudinally adjacent the fixed detector 20. For this purpose, the member 40 is preferably 20 grooved on each side, as indicated at 41 in Fig. 3, these grooves being adapted to receive a rib or projection 42 (Fig. 4) on the side of the fixed detector 20 and a similar projection 43 on an outer guide plate 44.

25 The member 40 is connected by a toggle link 45 to a toggle arm 46 pivoted at 47 to the slide 10 and having a laterally projecting arm 48 forming a bell crank or angle lever therewith. A compression spring 50 (Fig. 5) engages the front side of the arm 48 and normally holds the parts yieldingly in the position shown in Figs. 3 and 5.

The toggle arm 46 has a projection 51 adapted to engage the arm 26 of the movable detector 22 and normally prevent swinging movement of the detector away from the fixed detector 20. An adjustable rod or stud 52 is fixed to the front binder 53 of the shuttle box or to some other suitable part movable with the lay and under certain conditions engages the arm 48 of the toggle crank.

Having described the details of construction of my improved weft detecting mechanism, I will now describe the operation and advantages thereof. The normal running position of the parts is shown in Fig. 5, in which the broad smooth outer end of the contact member 40 engages the weft on 50 the weft carrier and receives the thrust thereof, the member 40 projecting rearwardly slightly beyond the point of the fixed detector 20 and the toothed edge of the movable detector 22. The toggle link 45 is in 55 firm contact with a portion of a rib 42, as clearly indicated in Fig. 3, thus locking the toggle from further movement and holding the contact member substantially fixed with relation to the slide 10.

60 The slide 10, being moved forward by the member 40 acts through the link 25 and the arms 28 and 32 to withdraw the plunger 33, permitting the floating lever 36 to reciprocate freely in the slot 35. When, however, the weft on the weft carrier is de-

pleted to a predetermined extent, the stud 52 engages the arm 48, breaking the toggle and moving the parts to the position shown in Fig. 6 in which the contact member 40 is withdrawn beyond the end of the regular detectors 20 and 22.

If sufficient weft then remains on the weft carrier, the movable detector 22 is held thereby from angular movement and the plunger 33 is withdrawn as before described. 75 When, however, the weft is substantially exhausted, the detector 22 swings freely upon its pivot 23, is shown in Fig. 7, and the plunger 33 remains in the path of the floating lever 36, as indicated in Fig. 1. The lever 36 thereupon engages the plunger 33 and moves about the point of engagement as a pivot raising the rod 39 and indicating substantial weft exhaustion as fully explained in my prior Patent No. 972,772. 85

Attention is called to the fact that the parts are always restored to the normal position shown in Figs. 3 and 5 upon every rearward movement of the lay and subsequently no re-setting or other attention is necessary after a transfer has been effected. All parts are exceedingly simple both in construction and operation and there is nothing about the device which can reasonably be expected to cause any difficulty in the operation of the loom.

Having thus described my invention and the advantages thereof, I do not wish to be limited to the details herein disclosed otherwise than as set forth in the claims, but what I claim is:—

1. In a loom, a weft detecting mechanism comprising a movable support, fixed and movable detectors mounted thereon, a supplementary weft contact member movably mounted on said support, means to hold said contact member from relative forward movement on said support when engaged by a weft carrier having a predetermined amount of weft thereon, thereby rendering said fixed and movable detectors inoperative, and means to disable said third member and to thereby render said fixed and movable detectors operative upon a predetermined weft depletion. 115

2. In a loom, a weft detecting mechanism comprising a movable support, fixed and movable detectors mounted thereon, a supplementary contact member movably mounted on said support, means to hold said contact member from relative forward movement on said support during normal running conditions, thereby rendering said fixed and movable detectors inoperative, and means to release said contact member for forward movement on said support upon predetermined weft depletion, thereby rendering said fixed and movable detectors operative. 125

3. In a loom, a weft detecting mechanism comprising a movable support, fixed and

movable detectors mounted thereon, a supplementary contact member movably mounted on said support, means to hold said contact member from relative forward movement on said support during normal running conditions, thereby rendering said fixed and movable detectors inoperative, and means to remove said member from operative position on said support when the weft on the running weft carrier reaches a predetermined state of depletion, thereby rendering said fixed and movable detectors operative.

4. In a loom, a weft detecting mechanism comprising a slide, fixed and movable detectors mounted thereon, a supplementary contact member movably mounted on said slide, a toggle lock effective to hold said contact member from relative forward movement on said slide during normal running conditions, and means to break said toggle upon predetermined weft depletion.

5. In a loom, a weft detecting mechanism comprising a slide, fixed and movable detectors mounted thereon, a supplementary contact member movably mounted on said slide, a toggle lock effective to hold said contact member from relative forward movement on said slide during normal running conditions, and means to break said toggle upon predetermined weft depletion, one of said toggle members while in holding position also holding said movable detector from angular movement.

6. In a loom, a weft detecting mechanism comprising a slide, fixed and movable detectors mounted thereon, a supplementary contact member movably mounted on said slide, a toggle lock effective to hold said contact member from relative forward movement on said slide during normal running conditions,

said lock including a member having a laterally projecting arm, and an engaging device movable with the lay and effective to swing said arm and break said toggle on predetermined weft depletion.

7. In a loom, a weft detecting mechanism comprising a slide, fixed and movable detectors mounted thereon, a supplementary contact member movably mounted on said slide, means to hold said contact member normally against movement relative to the slide and in position to engage the weft before the detectors engage the weft, so long as a predetermined amount of weft is present, and means carried by the lay and additional to the weft carrier, effective to unlock the supplementary contact member when less than a predetermined amount of weft is present and to move said contact member out of its rearward contacting position, thereby permitting the fixed and movable detectors to become operative.

8. In a loom, a weft detecting mechanism comprising a slide, fixed and movable detectors on said slide, a supplementary contact member movably mounted on said slide, means to hold said contact member normally rearward of the fixed and movable detectors to render the latter inoperative, and means carried by the lay and projecting in advance of the surface to be detected, effective to move said contact member to a relative forward position, thereby permitting the movable detector to have a detecting movement when less than a predetermined amount of weft is present.

In testimony whereof I have hereunto affixed my signature.

EPPA H. RYON.
